CLAIM

The ornamental design for a boat plug tool, as shown and described.

DESCRIPTION

FIG. 1 is a top perspective view of a boat plug tool, showing the new design;

FIG. 2 is a bottom perspective view thereof;

FIG. 3 is a left view thereof;

FIG. 4 is a front view thereof;

FIG. 5 is rear view thereof;

FIG. 6 is a top view thereof; and,

FIG. 7 is a bottom view thereof.

The broken lines in the drawings illustrate portions of the boat plug tool which form no part of the claimed design.
